PROCESS OF MAKING SOAP

Benjamin Clayton, San Marino, Calif., assignor
to Benjamin Clayton, doing business as Re-
fining, Unincorporated

Application December 11, 1946, Serial No. 715,564

4 Claims. (Cl. 260—417)

1

This invention relates to a process of making soap and more particularly, to a high temperature process of saponifying glycerides in which a neutral or somewhat alkaline soap is produced while minimizing the destruction of glycerine.

In high temperature processes of making soap and recovering glycerine by vaporization thereof from molten anhydrous soap, it has been difficult to produce a high quality soap while avoiding excessive destruction of glycerine. Caustic alkalies have been considered necessary for the saponification of glycerides as it is known that non-caustic alkaline compounds, such as alkali metal carbonates, do not saponify glycerides to any appreciable extent or that the reaction is so slow as to render the process impracticable in conventional soap making processes in which the temperatures employed do not greatly exceed the boiling point of water. In fact soda ash and other so-called non-saponifying alkalies such as tri-sodium phosphate, di-sodium phosphate, etc., have been employed or suggested as neutralizing agents for the fatty acids in the refining of vegetable oils because of their inertness to glycerides in order to prevent or minimize saponification of glycerides.

In high temperature continuous processes of making soap, for example as shown in my prior Patent 2,235,628, granted March 18, 1941, either a soap containing unsaponified glycerides or fatty acids or a soap containing free or unreacted alkali is produced unless the proportioning of alkali and saponifiable material is extremely accurate. If the amount of alkali is insufficient to convert all of the fatty acids of the glycerides into soap, i. e., insufficient to produce a neutral soap, the soap is of poor quality due to the thermal decomposition of the unsaponified fatty material at the high temperatures existing in the process. The production of a neutral soap in such a process using caustic alkali as the saponifying agent requires a small excess of the alkali over that theoretically required to combine with the fatty acids of the glycerides. At the high temperatures employed a small amount of the alkali combines with impurities in the glycerides which do not react with alkali in conventional soap making processes or in conventional tests to determine the saponification number of the fatty material. Caustic alkali, in excess, will react with glycerine when the latter is volatilized under the conditions prevailing in the vapor separating chamber. The latter two reactions proceed along with the main reaction of the alkali with the fatty acids liberated from the glycerides with the result that the 55

2

recovery of glycerine is substantially less than the theoretical recovery even when the small amount of glycerine which remains in undecomposed form in the soap is taken into consideration. Proportioning apparatus has been developed to a high degree of accuracy such that a neutral soap can be consistently produced but even the production of a neutral soap results in substantial destruction of glycerine.

10 Also, a small amount of free or unreacted alkali is usually desirable in the finished soap and in some cases a strongly alkaline soap is desired containing a relatively large amount of free alkali. The most satisfactory manner of uniformly distributing this alkali throughout the soap is to add the alkali during the saponifying reaction. This additional excess alkali also acts to destroy glycerine if added in the form of caustic alkali.

In accordance with the present invention I 20 have found that under the conditions existing in such high temperature processes, non-caustic alkalies, such as alkaline compounds of alkali metals, can be substituted for a part of the caustic alkali while still carrying the saponification reaction to completion. Such non-caustic alkalies do not react as rapidly as caustic alkalies but they also do not decompose glycerine to an extent approaching that of caustic alkali even at the high temperatures employed. A neutral soap 30 or a soap containing a substantial excess of alkali can be produced while minimizing destruction of glycerine. The major portion of the saponifying agent may still be caustic alkali but the amount of such caustic alkali is less than that required to react with the fatty acids of the glycerides. The caustic alkali reacts more rapidly with the glycerides so that the alkali which completes this reaction as well as that furnishing any excess for other reactions or any free alkali in the 40 finished soap is substantially all non-caustic alkali. The preferred operation is, therefore, to use somewhat less caustic alkali than necessary to saponify the glycerides in conjunction with sufficient non-caustic alkali to complete the saponification of the glycerides and furnish a small excess of alkali. By this process a high quality soap of high detergent qualities can be produced with negligible destruction of glycerine.

I have further found that the non-caustic alkali 50 may consist entirely or partially of soda ash even though carbon dioxide is liberated in the reaction between the soda ash and the fatty acids split from the glyceride molecule. By operating the process so that carbon dioxide has an opportunity to separate from the reaction mass,

the reaction can be carried to substantial completion. The high vacuum desirable for vaporizing glycerine from the soap does effectively remove the carbon dioxide from the reaction mass and, in general, the vacuum pumps usually employed in the vacuum system are adequate to discharge the carbon dioxide from the system although carbon dioxide absorption in the vacuum system may be employed, if necessary. Soda ash is the preferred alkali for completing the reaction and furnish any desired excess alkali in the present invention as it is relatively inexpensive and also modifies the characteristics of the heated soap to render the glycerine more easily distilled from the soap. Substantially complete vaporization of glycerine can be accomplished even without rendering molten the resulting anhydrous soap, thus enabling a powdered anhydrous soap to be directly produced.

It is, therefore, an object of the present invention to provide an improved process of saponifying glycerides with alkali under high temperature conditions in which glycerine is separated from the soap by vaporization thereof while minimizing destruction of glycerine.

Another object of the invention is to provide a high temperature rapid process of saponifying glycerides with alkali in which at least a portion of the alkali is of the type which minimizes the destruction of glycerine.

A further object of the invention is to provide an improved process of saponifying glycerides in which an excess of an alkali which minimizes the destruction of glycerine is employed under high temperature conditions.

A still further object of the invention is to provide an improved process of saponifying glycerides and recovering glycerine in which a greater recovery of glycerine is accomplished and a powdered anhydrous soap directly produced.

Other objects and advantages of the invention will appear in the following description of a preferred embodiment of the invention made in connection with the attached drawing which illustrates an apparatus suitable for carrying out the present invention.

Referring to the drawing, the apparatus may include a source of supply such as a tank 10 for saponifiable material and a source of supply such as a tank 11 for saponifying agent. In accordance with the present invention the saponifiable material may consist essentially of glycerides or may be a mixture of fatty or other saponifiable acids and glycerides. The saponifying agent is preferably predominantly a caustic alkali admixed with a small amount of an alkaline compound of an alkali metal, for example soda ash, but if an insoluble soap is desired the saponifying agent may include an alkaline earth metal hydroxide or alkaline compound thereof. The saponifiable material may be withdrawn from the tank 10 by means of a pump 12 and forced through a heat exchanger 13 which may be of any suitable type capable of rapidly heating a flowing stream and preferably comprises a coil 14 through which the material to be heated is passed and a casing 15 through which any suitable heating medium may be circulated. The saponifiable material is preferably heated to a relatively high temperature in the heat exchanger 13 and delivered to a mixer 16. The saponifying agent may be withdrawn from the tank 11 by means of a pump 17 and passed through a heat exchanger 18 and delivered to the mixer 16. The pumps 12 and 17 are shown as being driven by a variable speed

electric motor 19 with a speed change device 21 positioned between the pumps 12 and 17 although any suitable proportioning mechanism may be employed preferably that shown in the patent to Thurman No. 2,142,062 granted December 27, 1938. The mixer 16 is preferably a flow mixer of the type also disclosed in said patent, but may be any suitable type of mixer such as a closed mechanical agitator. The resulting mixture from the mixer 16 is preferably passed through another heat exchanger 22 wherein the temperature of the mixture is further raised and then passed through another pump 23 which serves as an additional mixing device as well as helping to overcome the pressure drop in the equipment. The mixture from the pump 23 is then preferably passed through another heat exchanger 24 and delivered into a vapor separating chamber 26.

The vapor separating chamber 26 is preferably provided with a lower conical portion 27 provided with a lower inclined wall against which the mixture from the heat exchanger 24 is directed by a plurality of nozzles 28. The lower conical portion 27 of the vapor separating chamber 26 is preferably surrounded by a heating jacket 29 through which any desired heating medium may be circulated to maintain the desired temperature in the vapor separating chamber 26. The vapor separating chamber 26 is also preferably provided with scrapers 31 secured to a shaft 32 driven through any suitable source of power, for example through a sprocket 33. Soap collecting in the vapor separating chamber is thus discharged into the casing 34 of a screw conveyor 35 which serves to deliver the soap from the process and seal the vapor separating chamber 26 against entrance of air. The casing 34 of the screw conveyor may be provided with a cooling jacket 37 through which any desired cooling medium such as water may be circulated.

The vapor separating chamber 26 may be provided with a condenser system including a condenser 38 connected to the vapor separating chamber 26 through a pipe 39, a receiver 41 connected to the condenser 38, a condenser 42 connected to the receiver 41, and a receiver 43 connected to the condenser 42. If soda ash or other carbonate is employed as part of the saponifying agent a carbon dioxide absorbing chamber 44 may be connected to the receiver 43, between such receiver and a vacuum pump 46 to reduce the load on the vacuum pump. The carbon dioxide absorbing tower 44 may be of any suitable type such as a bubble tower through which is passed a suitable carbon dioxide absorbing liquid. The preferred absorbing liquid is a solution of caustic soda which reacts with the carbon dioxide to form sodium carbonate. The resulting sodium carbonate solution may be employed as part of the saponifying agent or sold as a product of commerce. Other absorbing liquids such as hydroxides of other alkali or alkaline earth metals or certain amines or ethanolamines may, however, be used as the carbon dioxide absorbing agent.

In the preferred operation of the present invention for producing a sodium soap the saponifiable material is substantially all glyceride oil or fat although it may contain substantial quantities of free fatty acids. The greater the proportion of glycerides employed in the saponifiable material the greater the glycerine recovery. The saponifying agent is preferably a relatively concentrated aqueous solution of caustic soda containing sufficient soda ash to minimize destruction of glycer-

ine. Commercial soda ash either in solid form or in concentrated solution usually contains a small amount of soda ash as an impurity. Ordinarily the amount of soda ash is considerably less than 1% based on the total weight of alkali and in no case has commercial caustic soda sold for soap making processes been encountered in which the soda ash or other non-saponifying alkali present in the caustic soda even approached 2%. Caustic soda containing 2% soda ash and obtained by deliberately adding soda ash to commercial caustic soda to bring the soda ash content to this amount has no appreciable effect in reducing glycerine destruction in high temperature soap making operations. Caustic soda containing 5% of soda ash does, however, in all cases encountered reduce the destruction of glycerine to a very small amount, i. e., to an amount approaching that which laboratory experiments have shown should result if no caustic soda were present. This amount of 5% has, therefore, been adopted in commercial operations in accordance with the present invention. No precise lower limit on the effective amount of soda ash applicable to all glycerides or glyceride fatty mixtures can be given as the minimum amount of soda ash usable in a given case depends to a large extent upon the nature of the fatty material being saponified, for example, the amount of materials other than fatty acids and glycerine which will react with alkali under the conditions of operation. In most cases 3% soda ash will minimize glycerine destruction and sometimes even less is sufficient. In all cases more than 2% is required.

As to the upper limit of soda ash, 10% is in most cases a practical upper limit. Addition of soda ash in amounts greater than 5% have no substantial effect in further reducing destruction of glycerine and increase the amount of carbon dioxide which must be discharged from the vacuum system. Also, soda ash tends to precipitate out of concentrated caustic soda solution, for example 25° Bé. solutions when added in amounts above 10%. By reducing the concentration of the caustic soda solution, however, amounts of soda ash as great as 25% of the total alkali can be employed. While the proportions of the non-caustic to caustic alkali have been discussed, particularly with respect to caustic alkali and soda ash, these proportions are, in general, applicable to other non-caustic alkalies as well as other caustic alkalies.

The proportions of saponifiable material to total alkali are initially calculated from the saponification number of the saponifiable material by known formulas. Since the saponification number of the saponifiable material is determined at low temperatures, more alkali than indicated by such determination is required at high temperatures to produce a neutral soap because of reactions with impurities present and with a small amount of glycerine. For a neutral soap this additional alkali will vary with the nature of the saponifiable material but will usually be less than 1% based on the amount of saponifiable material. If an alkaline soap is desired, further alkali is added. This further alkali may range from 1/2% to 3% and should be non-caustic alkali particularly if the total alkali which is just sufficient to produce a neutral soap contains approximately the smallest amount of non-caustic alkali which will minimize glycerine destruction. The important consideration is that the caustic alkali be more than 2% and preferably 3% to 5% less than that required to produce a neutral soap, the

remainder of the alkali being non-caustic alkali. That is, there should be enough non-caustic alkali present to minimize attack on the glycerine by the alkali.

Both the saponifiable material and saponifying agent are preferably preheated in heat exchangers 13 and 18, respectively, to relatively high temperatures. For example, the saponifiable material may be heated to temperatures between 300° and 450° F. Because of the corrosive nature of the alkali it may be desirable to preheat this material to a somewhat lower temperature, for example 200° to 300°, although with corrosion resistant materials in the heat exchanger and pipe lines this temperature may be substantially the same as that for the saponifiable material. The temperature of the resulting mixture in the mixer 16 may therefore range between 300° and 450° F. and temperatures in the upper range are preferable.

In general, it is desirable to maintain sufficient pressure in the preheating heat-exchangers 13 and 18, the mixer 16, and the heat exchanger 22 to prevent any substantial vaporization of water although liberation of carbon dioxide may take place in the heat exchanger 22. The caustic alkali reacts rapidly with the glycerides to liberate glycerine and produce soap. At the temperatures maintained in the heat exchanger 22 substantially no destruction of glycerine by the caustic alkali is produced and even though the temperatures in the heat exchanger 22 are sufficiently high to cause caustic alkali to decompose glycerine, the caustic alkali reacts with the glycerides at a sufficiently rapid rate that it is consumed before substantial destruction of glycerine is produced. Sufficient soda ash likewise reacts with the glycerides in the heat exchanger 22 to substantially carry the saponification reaction to completion and a substantial amount of carbon dioxide is generated. This substantially completely saponified mixture is then preferably passed through another heat exchanger 24 in which the pressure is somewhat lowered and if necessary additional heat supplied to the mixture. Thus temperatures of the mixture leaving the heat exchanger 22 may be between 400° and 475° F. while the temperature of the mixture leaving the heat exchanger 24 may range between approximately 450° and 650° F. and is usually substantially above 500° F. The pressure in the heat exchanger 24 is preferably made sufficiently low that substantial amounts of water vapor are liberated therein and small amounts of carbon dioxide which might restrain the saponification reaction due to the law of mass action are likewise liberated. Thus a mixture of gases, vapors and soap containing a small amount of excess soda ash is discharged into the vapor separating chamber 26. All of the caustic alkali is rapidly used up in saponifying the glycerides so that the excess of alkali is substantially all soda ash.

The mixture delivered into the vapor separating chamber 26 may be at sufficiently high temperature to render the soap molten after glycerine and water vapor have been removed therefrom. However, the presence of the excess soda ash raises the melting point of the soap so that the soap containing excess soda ash can be recovered in powdered form after the glycerine and water vapors have been separated therefrom. It has been found that substantially neutral soap or even soap containing a small amount of unreacted glycerides or fatty acids or unreacted caustic soda should be of high enough temperatures to

be in molten form after the vapors have been removed therefrom if substantially complete separation of glycerine vapors is to be obtained. In accordance with the present invention, it has been further found that when a portion of the saponification is accomplished with soda ash and excess soda ash remains in the soap, glycerine and water vapors are substantially completely removed from the soap even though the soap is not of sufficiently high temperature to be in molten form after the vapors have been removed therefrom. Thus temperatures in the vapor separating chamber may be as low as 450° F. while still obtaining substantially complete separation of glycerine vapors, or may be as high as 600° F. or higher without destruction of glycerine while still producing a high quality soap. By correlating the excess amount of soda ash with the temperature and vacuum employed in the vapor separating chamber a substantially dry powdered soap which does not adhere to the chamber walls or scraper mechanism can be produced with substantially complete separation of glycerine vapor.

This soap may be discharged from the vapor separating chamber by means of the screw conveyor 35 and cooled during discharge below a temperature at which it will be damaged by contact with the atmosphere. Such a temperature is in the neighborhood of 120° F. Also, water may be introduced into the conveyor chamber 34 through a pipe 47 to assist in cooling the soap or to cool and hydrate the soap to any desired degree prior to discharge from the conveyor. The screw conveyor may be of the type shown in the Thurman Patent No. 2,190,615 granted February 13, 1940, and two or more conveyors may be used in series, if desired.

Vapors are withdrawn from the vapor separating chamber 26 through the pipe 39 at a rate sufficiently high to produce a relatively high vacuum in the vapor separating chamber, for example a vacuum of at least 28½ to 29 inches of mercury. By employing a series of condensers such as the condensers 38 and 42, glycerine and water vapors may be fractionally condensed. Thus a concentrated solution of glycerine or substantially pure glycerine may be withdrawn from the receiver 41 and the water condensed in the condenser 42 and withdrawn from the receiver 43. Incondensable gases, which may be substantially all carbon dioxide, if soda ash is used in the process, may then be passed through the carbon dioxide absorber 44 and any remaining gases exhausted from the system by the vacuum pump 46.

It has been found that glycerine destruction by caustic alkalies, for example caustic soda, becomes relatively rapid in the neighborhood of 500° F. For example, heating a solution containing 20% glycerine and 2.5% sodium hydroxide, under pressure to prevent evaporation, to 500° F. in fifteen minutes and then rapidly cooling, results in the destruction of approximately 2% of the glycerine. The amount of glycerine destroyed doubles for approximately each 25° F. increase in temperature above 500° F. where the heating in each case is carried out in fifteen minutes. The amount of destruction of glycerine increases substantially proportional to the concentration of sodium hydroxide and it also increases substantially proportional to the time at which the mixture is maintained at a given temperature. It has also been found that the presence of soap in the solution has substantially no effect upon the rate of glycerine destruction. It will thus be seen that the presence of any substantial excess of

caustic alkali in the reaction mixture containing glycerine at temperatures above approximately 500° F. results in a substantial destruction of glycerine.

On the other hand, it has been found under the same conditions of temperature, concentration, etc., that the destruction of glycerine by soda ash is approximately one-tenth of the destruction of glycerine by caustic soda. By employing less caustic soda than that necessary to saponify the glyceride and supplying the remaining alkali as well as an excess in the form of soda ash, the high temperature saponification may be carried on with negligible destruction of glycerine even though temperatures substantially above 500° F. are employed. The time during which the materials in the process are subjected to high temperatures is extremely small. Also, if a powdered anhydrous soap is desired the process can be carried on at temperatures below 550° while at the same time securing substantially complete recovery of glycerine.

As a specific example of the present process, a glyceride containing approximately 10% combined glycerine on the basis of the total fat was saponified in accordance with the present invention employing a final temperature of approximately 550° F. The alkali employed was an aqueous caustic soda solution containing 5% soda ash on the basis of the total alkali and having a concentration of 25° Bé. at room temperature. The proportions of alkali and saponifiable material were adjusted so that the resulting soap was slightly alkaline. The glycerine recovered by vaporization and condensation was 9% of the total fat and 0.75% glycerine on the same basis was left behind in the soap. Thus 0.25% glycerine was destroyed or on the basis of the total glycerine 2.5% was destroyed. When caustic soda alone is employed under the same conditions to produce a soap having the same alkalinity, the destruction of glycerine is approximately 25% or ten times as great. While soda ash is the preferred non-caustic alkali because of its cheapness and availability and modification of the properties of the resultant soap, other non-caustic alkalies such as other alkaline salts may be employed, for example di-sodium phosphate or tri-sodium phosphate to give substantially the same results.

This application is a continuation-in-part of my copending application Serial No. 435,679, filed March 21, 1942 which has now become abandoned.

55 While I have disclosed the preferred embodiment of my invention, it is understood that the details thereof may be varied within the scope of the following claims.

I claim:

60 1. A high temperature process of making soap and recovering glycerine, which comprises, reacting a fatty material consisting essentially of glycerides of fatty acids with a mixture of caustic and non-caustic alkali in an amount at least sufficient to completely react with said fatty material, said mixture being essentially caustic alkali with a minor amount of non-caustic alkali, the amount of caustic alkali being substantially less than that necessary to completely react with said fatty material and the amount of non-caustic alkali being between approximately 3% and 10% of the total alkali and sufficient to minimize destruction of glycerine at the temperature of reaction, completing said reaction at a temperature 70 at least as high as 450° F., and separating gly-

erine in vapor form under vacuum conditions from the reaction mass.

2. A high temperature process of making soap and recovering glycerine, which comprises, reacting a fatty material consisting essentially of glycerides of fatty acids with a mixture of caustic and non-caustic alkali in an amount at least sufficient to completely react with said fatty material, said mixture being essentially caustic alkali with a minor amount of non-caustic alkali, the amount of caustic alkali being substantially less than that necessary to completely react with said fatty material and the amount of non-caustic alkali being between 3% and 25% of the total alkali and sufficient to minimize destruction of glycerine at the temperature of reaction, completing said reaction at a temperature at least as high as 450° F., and separating glycerine in vapor form under vacuum conditions from the reaction mass.

3. A high temperature process of making soap and recovering glycerine, which comprises, reacting a fatty material consisting essentially of glycerides of fatty acids with a mixture of caustic and non-caustic alkali in an amount at least sufficient to completely react with said fatty material, said mixture being essentially caustic alkali with a minor amount of non-caustic alkali, the amount of caustic alkali being between approximately 90% and 97% of that necessary to produce a neutral soap, the remainder of the alkali being non-caustic alkali in an amount at least sufficient to produce said neutral soap, completing said reaction at a temperature at least as high as 450° F.,

and separating glycerine in vapor form under vacuum conditions from the reaction mass.

4. A high temperature process of making soap and recovering glycerine, which comprises, reacting a fatty material consisting essentially of glycerides of fatty acids with a mixture of caustic and non-caustic alkali in an amount at least sufficient to completely react with said fatty material, said mixture being essentially caustic soda with a minor amount of soda ash, the amount of caustic soda being between approximately 90% and 97% of that necessary to produce a neutral soap, the remainder of the alkali being soda ash in an amount at least sufficient to produce said neutral soap, completing said reaction at a temperature between approximately 500° and 650° F., and separating glycerine in vapor form under vacuum conditions from the reaction mass.
